(57) **CLAIM**

The ornamental design for an enclosure for refuse and recyclable containers, as shown and described.

DESCRIPTION

FIG. 1 is a front perspective view of an embodiment of an enclosure for refuse and recyclable containers; FIG. 2 is a top plan view of the enclosure for refuse and recyclable containers illustrated in FIG. 1; FIG. 3 is a front elevation view of the enclosure for refuse and recyclable containers illustrated in FIG. 1; FIG. 4 is a rear elevation view of the enclosure for refuse and recyclable containers illustrated in FIG. 1; FIG. 5 is a right side elevational view of the enclosure for refuse and recyclable containers illustrated in FIG. 1, the left side elevational view being a mirror image; and, FIG. 6 is a bottom plan view of the enclosure for refuse and recyclable containers illustrated in FIG. 1. The broken lines shown in FIGS. 1–6 are included for the purpose of illustrating environmental elements only and form no part of the claimed design.
